D. T. SCOTT

HEAVY OIL VAPORIZER

Filed March 13, 1924

Inventor
David T. Scott.

By Albert R. Dietrich
Attorney

UNITED STATES PATENT OFFICE.

DAVID T. SCOTT, OF MITCHELLS ISLAND, VANCOUVER, CANADA.

HEAVY-OIL VAPORIZER.

Application filed March 13, 1924, Serial No. 699,088, and in Canada December 24, 1923.

This invention relates to a means for vaporizing a heavy oil by the heat of the engine exhaust and for mixing the oil vapor with the required air for combustion in an internal combustion engine.

It comprises the combination with an ordinary carburetter of a chamber through which the engine exhaust passes before its delivery to the atmosphere, in which exhaust 10 heated chamber the oil and the air with which the oil is vaporized and which is to be mixed in the carburetter, is heated to a temperature approaching that of volatilization of a heavy fuel oil, and through which 15 exhaust heated chamber, the oil vapor, when mixed with the air for combustion, passes from the carburetter to the intake of the engine.

The particular means by which this result 20 is attained is fully described in the following specification, reference being made to the drawings by which it is accompanied, in which:

Fig. 1 is a vertical longitudinal section on 25 the line 1—1 in Fig. 3, looking in the direction of the arrow.

Fig. 2 is a vertical section on the line 2—2 in Fig. 1.

Fig. 3 is a vertical section on the line 30 3—3 in Fig. 1, and

Fig. 4 is a cross section on the line 4—4 in Fig. 1.

In these drawings 2 represents the carburetter, 3 the oil, and 4 the air, delivery 35 thereto, and 5 is the pipe through which the vaporized oil and air passes from the carburetter to the intake manifold of the engine and in which pipe it is heated by exposure to the exhaust of the engine in a 40 manner to be described. 6 is the valve which controls delivery from the carburetter.

This gas delivery pipe 5 from the carburetter passes through the ends of a substantially rectangular closed chamber 7. To 45 one end of this chamber 7 is secured a head 9 having two ducts 8 and 10, of which 8 is in communication with the pipe 5 and delivers to the engine intake, and the other 50 10, is connected to the exhaust of the engine to deliver the exhaust into the chamber 7 surrounding the tube 5. From the edge of this exhaust delivery port 10, which is further from the intake tube 5, partitions 11 and 12 extend to nearly the other end of the chamber 7 where they are connected to-

gether, leaving a space between 12 and the adjacent wall of the chamber 7, through which the exhaust gases may pass upward to deliver through a port 13 to the atmosphere, and a space 17 between 11 and 12 which is separated from the exhaust but is connected through a duct 19 to the air inlet 4 of the carburetter.

In one wall of the chamber 7 an opening, closable with a bolted door 15, affords access to the interior adjacent the tube 5. From each side of each door 15 a sheet iron casing 16 is carried around the other three sides of the chamber 7 to maintain an air space 18 between the walls of the chamber and the casing. The upper part of this air space 18 is open to the atmosphere adjacent the sides of the door 15, and opposite the door the air space is connected through 75 tubes 14 to the space 17 between the walls 11 and 12, which space is connected to the air intake to the carburetter through the duct 19.

An oil delivery tube 20 passes once or 80 more around the chamber 7 in the lower part of this air space 18 and is connected at 3 to the carburetter.

With this construction the exhaust of the engine enters the chamber at 7 and passes 85 downward around the gas delivery tube 5 and upward among the tubes 14 before its delivery to the atmosphere through the port 13. The waste heat of this exhaust thus passes through the walls of the chamber 90 and heats the air for combustion in the air space 18 through which the air for the carburetter is indrawn. It derives further heat from the exhaust as it passes through the tube 14 and while it passes through the space 95 17 before its delivery through the duct 19 to the carburetter at 4.

By this means both the oil and the air are heated to a temperature approaching that of volatilization of even a heavy oil before 100 delivery to the carburetter.

The oil vapor and air for combustion, as it is drawn from the carburetter, is further highly heated as it passes through the tube 5 to the intake of the engine, where the tube 5 is in contact with the hottest part of the exhaust, where it is delivered through the port 10 into the chamber 7.

The tube 5 will preferably be lengthwise ribbed, as shown in the drawing as affording 110 a greater heat conducting surface.

Under these conditions, not only can a

heavy fuel oil be effectively vaporized and without carbonization, but the exhaust from the engine is muffled and cooled before its delivery to the atmosphere, and the cooling of the exhaust gases prevents the muffling from causing a back pressure in the cylinders.

To enable an engine equipped with this heavy oil vaporizer to be started a supplementary carburetter 21 served at 22 with gasoline or a light hydrocarbon oil may be furnished and the gas delivery pipe 23 from this carburetter may be connected to the gas intake pipe 5. After the engine is started the supplementary carburetter may be cut off by the valve 24.

An aperture 25, see Fig. 1, affords direct communication between the exhaust admission 10 to the chamber 7 and the exit 13 therefrom, which aperture is closable with a valve 26 by which valve the amount of the exhaust gases delivered into the chamber 7 may be regulated to the engine requirements.

The position of this valve 26 may be controlled by a thermostat in the chamber 7 or in the gas delivery 5 to the engine intake.

By heating the fuel constituents for an internal combustion engine in a chamber through which the exhaust of the engine is passed before delivery of these constituents to a carburetter, a heavy fuel oil can be used in a more economical manner and be subject to more effective control to meet the varying requirements of an engine than where the heated oil is sprayed into a cylinder or into a heated duct or passage where the oil is liable to carbonize, unless the temperature and the proportions are very carefully regulated to the changing requirements.

Instead of delivering the exhaust gases through the upper port of the casing 15 and exhausting them to atmosphere through the port 13, if desired, this connection may be reversed and exhaust gas delivery effected at 13 and exhausted through the upper aperture of the casing.

Having now particularly described my invention, I hereby declare that what I claim as new and desire to be protected in by Letters Patent, is:

1. In an internal combustion engine, the combination with a carburetter, of a chamber through which the exhaust from the engine is passed, said chamber having a jacket space surrounding it and a compartment within

the chamber, which compartment is connected by tubes to the jacket space and to the air inlet of the carburetter, means for admitting air to the jacket space, means for heating oil in the jacket space of the chamber, and means for delivering the gaseous mixture of oil vapor and air from the carburetter separately through the chamber to the engine intake. 60

2. In an internal combustion engine, the combination with a carburetter, of a chamber through which the engine exhaust is delivered, said chamber having a jacket space surrounding it, and a compartment within the chamber which is in direct communication through tubes within the jacket space and with the air delivery to the carburetter, means admitting air to the jacket space, means within the chamber for heating the oil fuel before its delivery to the carburetter, and means within the chamber for separately heating the vaporized oil and air before delivery to the engine intake. 70

3. In combination with a carburetter, a vaporizer comprising a body having an elongated chamber, a gas delivery pipe passing through said chamber from end to end, one end of said pipe being connected to the outlet of the carburetter, said chamber having an exhaust inlet opening at one end, a cap having two ducts secured to said body, one duct connected with said pipe at its other end and the other duct connected with the exhaust inlet opening at the end chamber, 90 the first of the said cap's ducts adapted to connect with the intake of an engine while the other of its ducts is adapted for connection with the exhaust of the engine, said body having a duct leading from the end of 95 the said chamber farthest from the inlet opening back parallel to the chamber and delivering to atmosphere, a shell around three sides of said casing and enclosing a fresh air space, said casing having a chamber and a duct therefor connected with the air intake of the carburetter, and tubes from said fresh air space to said air chamber, said tubes passing through said last named duct to be heated by the exhaust gases, and an 100 oil feed pipe to the carburetter and having a portion coiled around said casing within the fresh air chamber, substantially as shown and described. 105

In testimony whereof I affix my signature.

DAVID T. SCOTT.
